DIRECTION INDICATOR FOR AUTOMOBILES OR THE LIKE.
APPLICATION FILED FEB. 24, 1919.
1,345,199. Patented

Patented June 29, 1929.

UNITED STATES PATENT OFFICE.

CLYDE W. LANDERS, OF PORTLAND, OREGON.

DIRECTION-INDICATOR FOR AUTOMOBILES OR THE LIKE.

1,345,199.

Specification of Letters Patent. Patented June 29, 1920.

Application filed February 24, 1919. Serial No. 278,753.

To all whom it may concern:

Be it known that I, CLYDE W. LANDERS, citizen of the United States, residing at Portland, in the county of Multnomah and State of Oregon, have invented certain new and useful Improvements in Direction-Indicators for Automobiles or the like, of which the following is a specification.

My invention relates to direction indicators, adapted for use upon automobiles or the like, while not necessarily restricted to this use.

An important object of the invention is to provide a device of the above mentioned character, embodying a pivoted visual indicator member, having means to turn the same in the desired direction, and means for preventing undue or improper oscillatory movement to the same, during the travel of the automobile or vehicle to which it is attached.

A further object of the invention is to provide a device of the above mentioned character which is attractive, of simple construction, strong and durable.

Other objects and advantages will be apparent during the course of the following description.

In the accompanying drawings forming a part of this specification and in which like numerals are employed to designate like parts throughout the same,

Figure 1 is a side elevation of a device embodying my invention, showing the same applied to the radiator of an automobile;

Fig. 2 is an end elevation of the same;

Fig. 3 is a central vertical longitudinal sectional view through the device;

Fig. 4 is a transverse sectional view taken on line 4-4 of Fig. 3;

Fig. 5 is a transverse sectional view taken on line 5-5 of Fig. 3;

Fig. 6 is a similar view taken on line 6-6 of Fig. 3;

Fig. 7 is a diagrammatic view showing the circuits included in the apparatus;

Fig. 8 is a front elevation of the switch;

Fig. 9 is an edge elevation of the same; and

Fig. 10 is a rear elevation of the same.

In the drawings, wherein for the purpose of illustration is shown a preferred embodiment of my invention, the numeral 15 designates a preferably conical support,

having a flat shank 16, held within a slotted bracket 17, having a base 18. This base is adapted to be secured to a portion of the automobile. In Fig. 1, the base 18 is shown as rigidly secured to the radiator of the automobile, but it is obvious that the invention is in no sense restricted to arranging the device at any particular location upon the automobile, as it may be secured in the rear or upon the sides thereof.

The conical support 15 serves to support the inner casing 19 of the device. This inner casing is preferably cylindrical and engages at its rear end with a flange 20, formed upon a rear head or end member 21, preferably formed of insulating material. The rear portion of the end member 21 is tapered, as shown at 22, for insertion within the conical support 15, these members being clamped together by a split ring 23, which is U-shaped in cross section. The ends of this ring are drawn together by a bolt 24 engaging brackets 25, as shown. The forward end of the inner casing 19 engages with a flange 26 of a forward head or end member 27. This end member 27 is formed of insulating material and is rigidly secured to the rear end member 21, by screws 28 or the like. It is thus seen that by unscrewing the screws 28, the end members are separated, and access readily had to the interior of the inner casing 19.

The numeral 29 designates an armature or rotor shaft, of a motor. The shaft carries a rotor 30, having a winding 31. The field of the motor comprises stators or field windings 32 and 33, as shown.

The device further comprises an outer pivoted casing 34, receiving the inner casing 19, as shown and having a central opening 35 to receive the forward end of the shaft 29. A plate 36 is arranged within and secured to the end 37 of the outer casing and engages a sleeve 38 carried by the shaft 29 and rigidly secured thereto. The outer casing 34 is clamped to the sleeve 38 and hence to the shaft 29 by means of a nut 39, as shown. It is obvious that when the armature shaft 29 turns the outer casing 34 will turn with it.

The outer casing 34 is prevented from partaking of undue or improper oscillatory movements by having its lower portion counterweighted. This is preferably ac-

complished by securing a strip of lead 40 in the lower portion of the casing 34, as clearly shown in Figs. 3 and 4. This counterweight 40 is heavier than the arrow-casing and elements carried thereby, to be described.

Means are provided to automatically return the outer casing 34 to its normal position when removed therefrom and released, comprising a coiled spring 41, arranged upon the sleeve 38 and having its opposite ends 42 projecting therefrom, and disposed upon opposite sides of a stationary pin 43, to contact therewith. This pin 43 is carried by the forward end member 27, as shown. The plate 36 is provided with a rearwardly projecting tongue 44, preferably stamped therefrom, which engages within a slot 45 of a crank arm 46, rigidly secured to the shaft 29 and depending therefrom. The slot 45 forms a tongue 47 stamped from the crank 46, and this tongue 47 is arranged between the ends 42 of the spring 41, to contact therewith. It is thus seen that when the outer casing 34 is turned in either direction, the tongue 47 will engage with the corresponding end 42 of the spring 41, placing it under tension, whereby this spring will serve to return the casing 34 to the normal position, when the casing is released.

Rigidly secured to the upper portion of the outer casing 34 is an arrow-casing 48, attached thereto by means of screws 49 or the like. This arrow-casing is provided with openings 50 and 51, formed in the front and side walls thereof, and spanned by translucent or transparent material 52, such as red celluloid, or the like.

A U-shaped bracket 53 is rigidly secured to the casing 34, within the arrow-casing 48, and insulated therefrom, by a bolt 54. This bolt has electrical connection with the bracket 53 and with a stationary spring contact 55, carried by the casing 34, and insulated therefrom. The spring contact 55 slidably engages a contact segment 56, secured to the end member 27, as shown. The U-shaped bracket 53 carries socket elements 57, receiving the outer terminal of an electric bulb 58, the inner terminal of which engages a contact 59, having electrical connection with the casing 34, and hence electrically connected or grounded to the casing 34 and shaft 29.

I provide a switch comprising a metallic casing 60, to be rigidly secured upon the automobile at a convenient location, such as on the steering column or dash. This casing 60 has an arrow extension 61. Arranged within the casing 60 is a block 62 of insulating material, having two stationary contacts 63 and 64 secured thereto. A lever or arm 65, formed of insulating material, has a metallic strip 66, secured upon the inner side thereof, and electrically connected with a binding post 67. The lever 65 has an arrow head 68, adapted to substantially coincide

with the arrow head 61 and to be shifted upon either side of the same, to bring the metallic strip 66 into electrical contact with either contact 63 or 64.

As clearly shown in Fig. 7, the numeral 69 designates a source of current, having one pole connected with a wire 70, having connection with the binding post 67. A wire 71 is connected with the contact 63 and is electrically connected with one end of the field winding 32, the opposite end of which is connected with a wire 72. This wire 72 has connection with the other field winding 32, the opposite end of which is connected with a wire 73, having connection with a terminal 74. Connected with the contact 64 is a wire 75, connected with one end of the field winding 33 to the right, the opposite end of which is connected with a wire 76, connected with one end of the other field winding 33, to the left, the opposite end of which is connected with a wire 77. This wire 77 is connected with the terminal 74. The terminal 74 has connection with a wire 78 (see Fig. 4). This wire 78 is electrically connected with one terminal of the electric bulb 58, by the elements hereinbefore described, the opposite terminal of the bulb being grounded to the casing 34 and armature shaft, as hereinbefore explained. Connected with the opposite pole of the source of current 69 is a wire 79, having connection with a stationary contact 80, having electrical connection with the armature shaft 29. The armature or rotor windings or coils 81 have one end 100 thereof grounded or electrically connected with the rotor 30 and shaft 29, by a clamping screw 81, while the opposite end thereof is connected with a wire 82, preferably coiled about the armature shaft 29, to allow of the turning movement of the armature shaft, and electrically connected with the terminal 74. It is thus seen that the wires 73, 77, 78 and 82 are all electrically connected by the terminal.

The operation of the apparatus is as follows:

When the switch lever 65 is in the central or normal position, the contact strip 66 disengages both stationary contacts 63 and 65, whereby the circuits for energizing the motor are open. The arrow-casing 50 is now in the vertical position, and is held therein without undue oscillatory movements, by the weight 40. If it is desired to swing the arrow-casing to the left, Figs. 2 and 7, the lever 65 is swung to the left until it engages stationary contact 63. A circuit is now closed for energizing the field windings 32 and for causing the bulb 58 to glow. The rotor 30 is now turned to the left swinging the casing 34 and arrow-casing in the same direction. In this closed circuit current flows from the positive side of the source of current 69, through wire 70, contact strip 130

66, contact 63, wire 71, field winding 32 to the left, wire 72, field winding 32 to the right, wire 73, terminal 74, wire 78, bulb 58, casing or ground 34, shaft 29, contact 80, 5 wire 79, and back to the source of current 69. At 74, a portion of the current passes through wire 82, armature windings 31, shaft 29, contact 80, wire 79, and back to the opposite pole of the source of current 10 69. When the lever 65 is swung to the right it engages the stationary contact 64 and a circuit is closed for energizing the field windings 33 and armature winding. This circuit is similar to that described in detail 15 and it is thought unnecessary to set it out. Attention is called to the fact that the current passes through the field windings 32 and 33 in opposite directions, when they are energized, while it passes through the armature winding in the same direction at all 20 times. Means are therefore provided to reverse the polarity of the field while maintaining the polarity of the armature constant whereby the armature or rotor may be 25 turned in opposite directions.

It is to be understood that the form of my invention herein shown and described is to be taken as a preferred example of the same, and that various changes in the shape, 30 size, and arrangement of parts may be resorted to without departing from the spirit of my invention or the scope of the subjoined claims.

Having thus described my invention I 35 claim:—

1. A direction indicator of the character described, comprising an inner casing, a support for the same, a motor arranged within the inner casing and including an armature 40 shaft, an outer casing receiving the inner casing and carried by the armature shaft to be turned thereby, and a signal element carried by the outer casing.

2. A direction indicator of the character 45 described, comprising an inner casing, a support for the same, a motor extending longitudinally within the inner casing and including an armature shaft projecting exteriorly thereof, an outer casing receiving the 50 inner casing and carried by the armature shaft to be turned thereby, a signal element secured to the upper portion of the outer casing and adapted to assume a substantially vertical normal position, and a weight 55 secured to the lower portion of the outer

casing and being heavier than the signal element.

3. A direction indicator of the character described, comprising an inner casing, a support for the same, a motor arranged within 60 the inner casing and including an armature shaft projecting to the exterior thereof, an outer casing receiving the inner casing in spaced relation, a signal element secured to the upper portion of the outer casing and 65 adapted to assume a substantially vertical normal position, a weight arranged within and secured to the lower portion of the outer casing between it and the inner casing, and yielding means for returning the outer casing to its normal starting position when moved therefrom and released.

4. A direction indicator of the character described, comprising a relatively stationary substantially cylindrical inner casing, a substantially cylindrical outer casing receiving the inner casing in spaced concentric relation, a motor arranged within the inner casing and having an armature shaft disposed centrally thereof and connected with the 80 outer casing centrally thereof, a signal element secured to the upper portion of the outer casing and adapted to assume a substantially vertical position, and a segmental weight arranged beneath the armature shaft 85 within the outer casing between it and the inner casing and secured to the outer casing and being heavier than the signal element.

5. A direction indicator of the character described, comprising a stationary casing, a 90 motor arranged therein and having an armature shaft extending to the exterior thereof, an outer casing receiving the inner casing and secured to the armature shaft, and an arrow-casing carried by the outer casing. 95

6. A direction indicator of the character described, comprising a stationary casing, a motor arranged therein and having an armature shaft, an outer casing connected with the armature shaft, an arrow-casing carried by the outer casing, an electric bulb arranged within the arrow-casing, and means to cause the bulb to glow when the outer casing is turned.

In testimony whereof I affix my signature 105
in presence of two witnesses.
